UNITED STATES PATENT OFFICE

FRANK A. TEEPLE, JR., OF ATLANTA, GEORGIA, ASSIGNOR TO SOUTHERN IRON & EQUIPMENT CO., OF ATLANTA, GEORGIA, A CORPORATION

LIQUID-FUEL-BURNER MECHANISM

Original application filed May 11, 1928, Serial No. 276,953. Divided and this application filed May 11, 1928. Serial No. 276,952.

This invention relates to a liquid fuel burner mechanism, designed primarily for use in connection with a cleaning unit forming the subject matter of my application filed May 11, 1928, Serial No. 276,953, of which this is a division, but it is to be understood that a liquid fuel burner mechanism, in accordance with this invention may be employed in any connection for which it is found applicable, and the invention has for its object to provide, in a manner as hereinafter set forth, a mechanism of such class including a liquid fuel holder forming the body portion of the burner element of the mechanism and whereby the vaporizing surface of the fuel varies with the height of the latter within the fuel holder.

A further object of the invention is to provide, in a manner as hereinafter set forth, a mechanism of the class referred to including a liquid fuel holder forming the body portion of the burner element of the mechanism and whereby the level of the fuel in the holder can be varied making it possible to regulate the fuel consumption and consequently heat generated by the combustion of the fuel.

A further object of the invention is to provide, in a manner as hereinafter set forth, a liquid fuel burner mechanism including means to provide for vortex action of the flame thereby obtaining a thorough mixing of the fuel vapor and air to bring about complete combustion and intense heat.

Further objects of the invention are to provide, in a manner as hereinafter set forth, a liquid fuel burner mechanism which is comparatively simple in its construction and arrangement, strong, durable, compact, adjustable, thoroughly efficient in its use, readily installed, conveniently assembled, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications

can be resorted to which fall within the scope of the claims hereunto appended.

In the drawings wherein like reference characters denote corresponding parts throughout the several views:

Figure 1 is a sectional elevation of a liquid fuel burner mechanism in accordance with this invention showing the adaptation thereof in connection with a cleaning unit.

Figure 2 is a top plan view of a liquid fuel burner mechanism in accordance with this invention.

Figure 3 is a cross sectional view thereof.

Figure 4 is a cross sectional view of the fuel controlling mechanism.

Figure 5 is a cross sectional view of the fuel controlling mechanism taken at right angles to that of Figure 4.

Figure 6 is a fragmentary view of the mechanism with the burner element and fuel control not shown.

A liquid fuel burner mechanism in accordance with this invention is illustrated by way of example in connection with a construction of cleaning unit as disclosed in my application aforesaid, and referring to Figure 1 of the drawings, 8 generally indicates a tank structure providing a compartment 9 for a body of cleaning solution 10. The tank structure 8 further includes a firebox 11, a combined dam and collecting means 12 which is positioned within the compartment 9 at the rear thereof, a valved discharge pipe for the combined dam and collecting means 12 and which is indicated at 13, a valved drain pipe 14 which communicates with the compartment 9 below the combined dam and collecting means 12 and further communicates with the discharge pipe 13, a liquid fuel reservoir 14 which is suspended from and also spaced from one side of the tank structure 8, a closure 15 for the lower portion of the front of the tank structure 8 and which is provided with a lining of refractory material 16' and a valved feed line leading from the reservoir 14 and which is indicated at 17'. The valved feed line for the liquid fuel opens into the liquid fuel burner mechanism in accordance with this invention and can flex.

The foregoing elements of the cleaning

unit are specifically referred to in my application aforesaid and it is thought unnecessary to specifically describe the same herein, other than to state that the liquid fuel burner mechanism, in accordance with this invention, is positioned at the front of the firebox 11 in the same manner with respect to the closure 15 as is set forth in my application aforesaid.

10 The liquid fuel burner mechanism includes a drip pan, a burner element, an adjustable combined draft regulator and deflector member, and a fuel feed control.

15 The drip pan, which also constitutes a support for the burner element and combined draft regulating and deflecting member consists of a bottom 16, a back wall 17, a pair of side walls 18, 19 and a front wall 20 which is of less height than the height of the back wall 17. The rear portion of each side wall is of greater height than the remaining portion thereof and said part of greater height is indicated at 21. Each side wall at its top is formed with a semi-circular cut-out 22 and with the edge thereof merging into the part 21 of greater height of the side wall. Each side wall of the pan, is provided in its top edge at its rear with a V-shaped notch 23 of appropriate depth. Each side 25 wall of the drip pan at its upper outer corner is formed with an opening 24 for the passage of a holdfast means, not shown, for connecting it to the front 15. The front wall 20 between its vertical median and the side wall 19 is formed with a vertically disposed notch 25 having its base beveled as at 26. Formed integral with the bottom 16 and the inner face of the front wall 20 is a bracing web 27. The drip pan when seated in position projects a 30 substantial distance from the front end of the firebox 11.

35 The burner element includes a trough-shaped body portion consisting of a pair of semi-circular or segmental end pieces 28, 29 which are seated in the semi-circular cutout portions 22 formed in the top of the side walls 18, 19. Formed integral with the end pieces 28, 29 are a pair of wall forming members one consisting of an inclined lower portion 30 40 and a vertically disposed upper part 31, and the other consisting of an inclined lower portion 32 and a vertically disposed upper part 33. The portions 30, 32 are oppositely disposed with respect to each other and the part 33 is of less height than the part 31 and arranged rearwardly thereof. The construction referred to in connection with the burner element provides the body portion thereof of 45 substantially V-shaped cross section. Formed integral with the body portion of the burner element, and spaced from the end pieces 28, 29 are semi-circular flanges 34 which are arranged adjacent the inner faces of the sides 50 55 60 65 65 18, 19 of the drip pan and function to prevent

the bodily shifting of the burner element relative to the drip pan. See Figure 2.

Extending through the bottom of the body portion of the burner element, at the longitudinal center thereof and centrally with respect thereto is a vertically disposed nozzle 35 for supplying liquid fuel 36 to the body portion of the burner element. The lower end of the nozzle 35 is connected to a feed pipe 36 which leads from the fuel feed control to be presently referred to.

The adjustable combined draft regulator and deflector member consists of a pair of side plates 37 substantially quadrangular in contour and which are connected together by an arcuate web 38 spaced from but in proximity to the top and rear edge of each of said side plates.

The web 38 at its top terminates in a forwardly directed, inclined flange 39 having its ends integral with the inner face of the side plates 37. Projecting from the web 38 at a point an appropriate distance above the lower edge thereof is a rearwardly directed right angularly disposed flange 40 having its ends integral with the inner faces of the side plates 37. The flanges 39 and 40 are also flush with the top and rear edges respectively of the side plates 37. The lower edge of the web 38 terminates an appropriate distance above the bottom edges of the side plates 37. The lower edge or bottom of the web 38 is seated in the notches 23 whereby said combined draft regulator and deflector member can be shifted in either direction upon the drip pan. The web 38 is arranged over and extends rearwardly from the burner element, as well as being spaced therefrom. The side plates 37 project rearwardly from the back wall 17 of the drip pan.

The adjusting means for the combined draft regulator and deflector member consists of a shifting lever of compound curvature and referred to generally at 41. The pivot for the lever 41 is indicated at 42, and that part of the lever 41 above the pivot 42, and which is indicated at 43 is of greater length than that part of the lever 41, below the pivot 42 and which is indicated at 44. The part 43 is reversely curved with respect to the part 44. The pivot 42 of the lever 41 is mounted in cutout portions 45 formed in the top edges 46 of a pair of vertically disposed, opposed, spaced supports 47 which are formed integral with the bottom 16 and rear wall 17 of the drip pan, but said supports 47 are of less height than the height of the wall 17. The cutout portions 45 are arranged in the forward part of the top edges 46 of the supports 47. The lever 41 has the part 44 thereof positioned between the supports 47 and said part 44 has its lower end spaced an appropriate distance above the bottom 16 of the drip pan.

The lever 41 is shifted by a bar 48 having

its rear end provided with a pin 49 which seats in the rear edge of the part 44 of the lever 41. The bar 48 projects forwardly between a pair of guide members 50 which are secured to the upper face of the bottom 16 and rear face of the front wall 20 of the drip pan. The lower edge of the bar 48 is provided with a set of teeth 51 selectively engaging with the beveled base 26 of the notch 25 for the purpose of latching the bar 48 from movement whereby the lever 41 will be set in its adjusted position, and the latter is positioned in close proximity to the forward end of the web 38 for the purpose of shifting or rather adjusting the combined draft regulator and deflector member when desired. The member can be adjusted to and from with respect to the burner element. The outer end of the bar 48 is provided with a handle member 52.

The fuel feed control comprises a housing 53 formed with a depending portion 54 having arranged therein a partition 55 forming an intake chamber 56 for the liquid fuel from the reservoir 14. The line 17' is connected to housing 14 and opens into the chamber 56. That portion of the interior of the housing 53, other than the chamber 56, constitutes a float chamber 57 and the liquid fuel is supplied to the chamber 57 through a valve controlled outlet 58 formed in the top of the chamber 56. A controlling valve for the opening 58 is indicated at 59, and which is carried by a stem 60, provided with an enlarged portion 61, which travels through a guide member 62. The stem 60 is provided at its upper portion with a pair of spaced collars 63 between which is arranged the forked end 64 of a pivoted lever arm 65 which is attached by the holdfast device 66 to a controlling float 67 for the valve 59. The feed pipe 36 communicates with the float chamber 57.

Connected to and projecting forwardly from the front wall 20 of the drip pan, is a supporting bracket 68 having a vertically disposed tubular portion 69 of cylindrical cross section. Arranged on the bracket 68 and surrounding the tubular portion 69 is a cam member 70 capable of being shifted horizontally about the tubular portion 69. The cam member 70 is provided with a handle 71. Co-acting with the cam member 70 is a cam member 72 upon which the housing 53 is mounted. Secured to the housing 53 and extending into the tubular portion 69 is a stem 74 carrying a fixed collar 75, and surrounding the stem 74 and interposed between the collar 75 and the top of the tubular portion 69 is a coiled spring 76 which functions to maintain the cam piece 70 against the cam piece 72 and further functions to pull the housing 53 downwardly. The cam pieces 70, 72 coact, when the cam piece 70 is revolved to elevate or lower the housing 53 thereby changing the level of the liquid fuel within the chamber 57 and also

within the body portion of the burner element. The level of the fluid in the chamber 57 and in the body portion of the burner is such that one will be in alignment with the other as indicated by broken line Figure 3.

The rise and fall of the float 67, within the chamber 57 will control the valve 59 to regulate the flow of the fuel from the chamber 56 into the chamber 57 or to cut off the supply of fuel to the chamber 57.

The fuel from the reservoir 14 flows to the housing 53 by gravity.

The height of the fuel in the float chamber at which the valve 59 cuts off is constant and since the float chamber is connected directly with the body portion of the burner element the height of the fuel in the burner element is practically the same as that in the float chamber.

In order to change the level of the fuel in the burner element it is necessary to change the height of the housing 53. This is accomplished by the cams 70, 72 in the manner as before stated. The upward shift of the housing 53 is had against the action of the spring 76. The cam members 70, 72 are so constructed that their action will never raise the housing 53 to a height whereby the liquid fuel will be raised high enough to overflow the burner element. The line 17' will flex sufficiently to permit of the housing 53 being elevated and owing to the fact that the burner element is pivotally supported upon the sides of the drip pan sufficient flexibility is had when the housing 53 is elevated or lowered. The connection between the burner element and the housing 53 is such that the burner element is plumb level when the fuel is at its maximum level and is slightly tilted when the housing is lowered.

The combined draft regulator and deflector member provides for deflecting a draft, for regulating the amount of air to be used for combustion and for directing the flame against the hot refractory material 16' which forms a lining for the closure 15 and which in turn deflects the flame upward and backward. The arrows in Figure 1 show general flame action. The results of this vortex action of the flame is that it brings about a thorough mixing of the fuel vapor and air, and this in the presence of the refractory material of the front, which becomes extremely hot, reflects and radiates this heat into the said vortex, brings about a complete combustion and creates an intense heat.

The burner element is to be disposed transversely across the width of the firebox and the flame as it travels toward the stack spreads itself out evenly over the whole width of the box, giving a more uniform heat to all parts of the heating surface. Further the design and location of stack as illustrated aids the flame action.

It is thought the many advantages of a

liquid fuel burner mechanism, in accordance with this invention, can be readily understood, and although the preferred embodiment of the invention is as illustrated and described, yet it is to be understood that changes in the details of construction can be had which fall within the scope of the invention as claimed.

What I claim is:

10. 1. A liquid fuel burner mechanism comprising a burner element of trough-like cross section for receiving a liquid fuel and having means at its ends to prevent the bodily shifting thereof lengthwise when mounted on a support therefor, a liquid fuel feed control communicating with said element, means for vertically adjusting said control for varying the height of the level of the liquid fuel in said element, a combined draft regulator and deflector member positioned above and rearwardly of said element, and a support common to said member and element.
15. 2. A liquid fuel burner mechanism comprising a burner element for containing a liquid fuel, a liquid fuel feed control including a chamber for containing a liquid fuel, means for establishing communication between the interior of the burner element and said chamber to provide for the level of the liquid in the burner element to correspond to the level of the liquid in said chamber, means supporting and acting on said chamber to vertically adjust said chamber for varying the level of the liquid therein and in said burner element, a combined draft regulator and deflector member arranged in spaced relation with respect to the burner element and further positioned thereover and rearwardly with respect thereto, and a support common to said element, feed control and means.
20. 3. A liquid fuel burner mechanism comprising a burner element for containing a liquid fuel, a liquid fuel feed control including a chamber for containing a liquid fuel, means for establishing communication between the interior of the burner element and said chamber to provide for the level of the liquid in the burner element to correspond to the level of the liquid in said chamber, means supporting and acting on said chamber to vertically adjust said chamber for varying the level of the liquid therein and in said burner element, a drip pan structure for pivotally supporting said element, and a support for said means connected with the drip pan structure.
25. 4. A liquid fuel burner mechanism comprising a burner element containing a liquid fuel, a liquid fuel feed control including a chamber for containing a liquid fuel, means for establishing communication between the interior of the burner element and said chamber to provide for the level of the liquid in the burner element to correspond to the level of the liquid in said chamber, means supporting and acting on said chamber to vertically adjust said chamber for varying the level of the liquid therein and in said burner element, a combined draft regulator and deflector member arranged in spaced relation with respect to the burner element, a drip pan for pivotally supporting said element and said member and a supporting element extended from said drip pan for said means.
30. 5. A liquid fuel burner mechanism comprising a burner element for containing a liquid fuel, a liquid fuel feed control including a chamber for containing a liquid fuel, means for establishing communication between the interior of the burner element and said chamber to provide for the level of the liquid in the burner element to correspond to the level of the liquid in said chamber, means supporting and acting on the control for vertically adjusting said chamber for varying the level of the liquid therein and in said burner element, an adjustable combined draft regulator and deflector member arranged in spaced relation with respect to the burner element, a drip pan for supporting said element, and means pivotally supported by and capable of being latched to said drip pan for adjusting said member.
35. 6. A liquid fuel burner mechanism comprising a burner element for containing a liquid fuel, a liquid fuel feed control including a chamber for containing a liquid fuel, means for establishing communication between the interior of the burner element and said chamber to provide for the level of the liquid in the burner element to correspond to the level of the liquid in said chamber, means supporting and acting on the control for vertically adjusting said chamber for varying the level of the liquid therein and in said burner element, an adjustable combined draft regulator and deflector member arranged in spaced relation with respect to the burner element, a drip pan for pivotally supporting said element and said member, and means pivotally supported by and capable of being latched to said drip pan for adjusting said member.
40. 7. In a liquid fuel burner mechanism a pivotally supported burner element of trough-like form adapted to contain a liquid fuel, vertically adjustable means for supplying a liquid fuel upwardly into and for varying the level of the liquid fuel in said element, and a pivotally supported, combined draft regulator and deflector member arranged in superposed relation with respect to and spaced from said burner element.
45. 8. In a liquid fuel burner mechanism a pivotally supported burner element of trough-like form adapted to contain a liquid fuel, vertically adjustable means for supplying a liquid fuel upwardly into and for varying the level of the liquid fuel in said element, a pivotally supported, combined draft regulator and deflector member arranged in superposed relation with respect to and spaced from said burner element.

- superposed relation with respect to and spaced from said burner element, and a drip pan positioned below said burner element and constituting a common support for said element and for said member. 5
9. In a liquid fuel burner mechanism a pivotally supported burner element of trough-like form adapted to contain liquid fuel, a cam actuated spring controlled, vertically adjustable means for supplying liquid fuel to and for varying the level of the liquid fuel in said element, and a pivotally supported combined draft regulator and deflector member arranged in superposed relation with respect to, spaced from and extended rearwardly from said burner element. 10
10. In a liquid fuel burner mechanism a pivotally supported burner element of trough-like form adapted to contain liquid fuel, a cam actuated spring controlled, vertically adjustable means for supplying liquid fuel to and for varying the level of the liquid fuel in said element, a pivotally supported combined draft regulator and deflector member arranged in superposed relation with respect to, spaced from and extended rearwardly from said burner element, and a drip pan arranged below said burner element and constituting a common support for said element and member. 20
11. In a liquid fuel burner mechanism a pivotally supported burner element of trough-like form adapted to contain a liquid fuel, vertically adjustable means for supplying a liquid fuel to and for varying the level of the liquid fuel in said element, a pivotally supported combined draft regulator and deflector member arranged in superposed relation with respect to and spaced from said burner element, a drip pan positioned below said burner element and constituting a common support for said element and for said member, and adjusting means for said member, said adjusting means pivotally supported 30

13. In a liquid fuel burner mechanism a pivotally supported burner element of trough-like form adapted to contain a liquid fuel, vertically adjustable means for supplying a liquid fuel to and for varying the level of the liquid fuel in said element, a pivotally supported combined draft regulator and deflector member arranged in superposed relation with respect to and spaced from said burner element, and said burner element having its rear portion of less height than its forward portion. 13
14. In a liquid fuel burner mechanism a pivotally supported burner element of trough-like form adapted to contain liquid fuel, a spring controlled, vertically adjustable means for supplying liquid fuel to and for varying the level of the liquid fuel in said element, and said burner element having its rear portion of less height than its forward portion. 14
15. In a liquid fuel burner mechanism a pivotally supported burner element of trough-like form adapted to contain liquid fuel, a spring controlled, vertically adjustable means for supplying liquid fuel to and for varying the level of the liquid fuel in said element, a pivotally supported combined draft regulator and deflector member arranged in superposed relation with respect to, spaced from and extended rearwardly from said burner element, a drip pan arranged below said burner element and constituting a common support for said element and member, adjusting means for said member, said adjusting means pivotally supported on said drip pan and further capable of being latched thereto to maintain said means in adjusted position, and said burner element having its rear portion of less height than its forward portion. 15
- In testimony whereof, I affix my signature hereto.
